(57) **CLAIM**

I claim the ornamental design for a slot for toy bricks, as shown and described.

DESCRIPTION

FIG. 1 is a perspective view of a slot for toy bricks.

FIG. 2 is a front view of the present invention as shown FIG. 1.

FIG. 3 is a top view of the present invention as shown in FIG. 1.

FIG. 4 is a bottom view of the present invention as shown in FIG. 1.

FIG. 5 is a perspective view of a slot design in a plurality of toy bricks.

FIG. 6 is a front view of the present invention as shown in FIG. 5.

FIG. 7 is a top view of the present invention as shown in FIG. 5.

FIG. 8 is a bottom view of the present invention as shown in FIG. 5; and,

FIG. 9 is a perspective view of the present invention as shown in FIG. 5 with a plurality of wires inserted into the slot design as intended.

The dash-dot broken lines immediately adjacent the shaded areas represent the bounds of the claim and all other broken lines represent the environment in which the article resides. None of the broken lines form a part of the claimed design.
